UNITED STATES PATENT OFFICE.

ANNA E. WOOD, OF CINCINNATI, OHIO.

BOOK-HOLDER.

1,239,655.

Specification of Letters Patent. Patented Sept. 11, 1917.

Application filed July 3, 1916. Serial No. 107,328.

To all whom it may concern:

Be it known that I, ANNA E. WOOD, a citizen of the United States, and residing at Cincinnati, in the county of Hamilton and State 5 of Ohio, have invented a new and useful Improvement in Book-Holders, of which the following specification is a full disclosure.

My invention relates to a bookholder in the nature of an improvement of the device 10 illustrated in my former patent, numbered 1,035,290, dated August 13, 1912.

The objects of the invention are to improve the cover holding provision, to render more simple and convenient the adjustments, 15 to avoid the necessity of using elastic tapes, or the like, and more specifically, to provide a simple means, such as a continuous cord for holding the book open in reading position, enabling the leaf turning without readjust- 20 ment, the same instrumentality serving to secure the sliding base in adjusted position to accommodate the holder to different sizes of books and also serving to adjustably sup- 25 port the holder relative to the reader, at the correct focal distance and angle of vision, for either a sitting or reclining position.

The features of the invention are more fully set forth in the description of the accompanying drawings, forming a part of 30 this specification, in which:—

Figure 1 is a front elevation.

Fig. 2 is a side elevation.

Fig. 3 is a top plan view.

Fig. 4 is a detail section on line 4—4, 35 Fig. 1.

The legs 1, 2, are connected by rigid cross-bars 3, 4, 5, secured to the outer leg surfaces against which the book covers rest the bottom edge of the book resting on the 40 adjustable base 6. Preferably the base is formed with the bifurcated ends 7, 8, between which the legs pass, and with a vertical ledge 9, making the base preferably of bracket shape, and the base may be formed 45 of one or more pieces as desired.

The means for engaging the opened up book covers comprise two strips 10, 11, the outer ends being secured to the legs upon the side opposite to the side of securedance of the 50 cross strips 3, 4, 5, and preferably opposite or adjacent to one of these cross strips in position to transversely engage a medial portion of the book covers 12, 13, the book binding 14, lying between the opposing inner 55 ends of the strips 10, 11, so that the strip 5 engages the back of the book covers and

binding, and the strips 10, 11, engage the inside of the book covers toward the binding, the reading pages 14' projecting out from the space between the ends of the strips 10, 11, the pages to be opened at the reading point and held in open position against the outer surfaces of the strips 10, 11. The base 6 is preferably provided at each end with the pairs of eyes 15, 16, adjacent the legs respectively, there being an eye 17 on each of the outer ends of the strips 10, 11, adjacent the legs respectively, the eye groups 15, 16, 17, being preferably disposed to define the apices of an isosceles triangle 70 upon each side of the holder. At the top of the right hand leg 2, is a hook 18, there being a similar hook 19 at the top of the other leg, and one of these hooks, the left hand one as shown, being adjustably screwed 75 into the leg and provided with a boss 20 for holding the cord in adjusted position against the leg.

One end of the cord is preferably secured to the right hand eye 17, and the other end 80 is detachably secured to the top right hand hook 18. The cord passes downwardly from eye 17, through eyes 15, 16, on the right hand side, then upwardly through eye 17 across the holder, running parallel with 85 strips 10, 11, through eye 17, on the left, then downwardly through eyes 15, 16, returning upwardly through eye 17, then upwardly to be looped under the clamp boss 20, of screw hook 19, from whence it is pref- 90 erably looped around the pillow or chair back for the reader, the return end being secured to right hand hook 18, the holding loop length being adjustable to suit individual requirements as to comfort, angle, 95 distance, reading position or couch or chair.

The cord arrangement relative to the slide-eyes provides a tackle on each side for securely and adjustably supporting the base, the adjusted position, after determination, 100 being fixed by securing the cord between the clamp hook 19 and the top of leg 1. The cord portion running parallel to cover holding strips 10, 11, holding the book pages open at the reading place, and it can be relaxed sufficiently to enable the pages to be turned. The strips 10, 11, of course, pass in rear of the reading matter so that only 105 the cord runs across the pages.

The holder is preferably of light wood, 110 suitable to the use of an invalid, and straddles the lap of the reader, the legs prefer-

ably having the hinges 22 for folding the holder into packing compass.

The manipulation of the cord effects all 5 adjustments in such a simple manner as to become subconscious after short usage, requiring no skill or labor and giving the greatest comfort with the least effort of mind or body.

The cord is durable and easily renewable, 10 and the use of the holder practically eliminates all manual effort incident to reading a book or magazine, the book can be left in the holder, open at the proper place, and the reading resumed by simply picking up 15 and attaching the holder, there being no occasion to readjust the cord after the initial adaptation to an individual requirement.

I claim:—

1. A bookholder comprising legs, the upper portion being connected by cross-bars, 20 providing a body straddling and a book holding portion, cover engaging strips secured at their outer ends to the sides of the bookholder, their inner ends being spaced, 25 a base adjustable on the legs below said strips, a cord slidably connecting the base

with the holder, for adjusting the base, a portion of the cord passing across the holder, and means for securing the cord to the holder to hold the base in adjusted position and to adjustably suspend the upper end of the holder relative to the body of the reader. 30

2. A bookholder comprising legs connected by cross bars providing a book holding and body straddling portion, cover engaging strips having their outer ends connected to the holder and the inner ends spaced, to hold the covers between the cross bars and strips and to enable the reading matter to 40 be projected beyond the strips, and a cord adjustably connected with the holder and providing a body engaging loop and a page engaging span for holding the pages open in reading position. 45

In witness whereof, I hereunto subscribe my name, as attested by the two subscribing witnesses.

ANNA E. WOOD.
